(57) **CLAIM**

The ornamental design for a light emitting diode module, as shown.

DESCRIPTION

FIG. 1 is a perspective view of a light emitting diode module showing my new design;

FIG. 2 is a front view thereof;

FIG. 3 is a rear view thereof;

FIG. 4 is a left side view thereof; and,

FIG. 5 is a top view thereof.

A right side view is symmetry to the left side view, and a bottom view is symmetry to the top view, thus the right side view and the bottom view are omitted.
